UNITED STATES PATENT OFFICE

2,669,762

METHOD FOR MAKING WARE BY CASTING

Andrew R. Blackburn and Richard E. Steele,
Columbus, Ohio

Application February 5, 1953, Serial No. 335,292

1 Claim. (Cl. 25—29)

1

The present invention relates to the manufacture of ceramic-ware and has particular reference to those methods commonly known in the art as gravity solid casting and pressure solid casting each of which is employed for the forming of "green" ware requiring subsequent finishing treatment.

The present application is related to United States Patent No. 2,584,109, entitled: Method and Apparatus for Making Ware, issued February 5, 1952, and contains subject matter in the disclosure common to both said patent and the instant application for patent.

In both solid casting methods as presently employed the formed object is separated finally from the mold by the shrinkage action inherent in the object upon losing a portion of its water of plasticity. However certain mold sections can be removed from contact with the ware before the ware shrinkage has progressed to any appreciable degree, in order to prevent contraction of the object about the mold section and without damaging the easily deformed object as long as the object is sufficiently supported by the remaining mold parts. The shrinkage characteristics and water retentive properties of the different slip or casting preparations vary considerably. This factor, in addition to the reconditioning period required for a mold to free itself of its held water and thus restore its absorption properties has prevented the rapid production of ceramic ware from a one mold unit and it has been necessary to employ large numbers of molds in an object forming operation in order to overcome to some extent the delay inherent in shrinkage release of objects from molds.

It follows that multiple porous molds have been employed to accelerate water absorption from a slip. Shrinkage of the formed object thus becomes a function of the porosity of the mold and the water retention capabilities of the cast object. While the production rate is thus accelerated, the presence of the two variable factors effecting shrinkage contribute to a lack of uniformity in the end product.

This is especially the case with the molding of objects having different thickness measurements in which the overall shrinkage rate is impossible to anticipate, except by tedious experiment with different types of casting materials and repeated object casting until a perfect object is produced. Generally, irregular shrinkage results in a high percentage of breakage during and subsequent to removing the object from the mold faces, and shattering during the finish-

2

ing operations from stresses developed in the ware structure. This is particularly the case with ware having, for example, a thin base and thickened sides, or vice versa.

5 Solid casting regardless of whether the slip is forced into a cavity by gravity only or injected into a cavity by elevated pressures, above that of the gravity feed is generally conducted at present along the following lines. The slip or fluid casting preparation is introduced or injected into an object forming cavity of the mold. The mold usually consists of two or more sections and is made from one of the suitable gypsum plasters or other suitable mold material. The 10 slip which may be prepared from a variety of ceramic raw materials, and well known to the art, is characterized by a higher specific gravity than that type required for ordinary draincasting and may in the case of pressure casting have a "livery" consistency. In pressure feed casting there is no need for the slip to flow freely.

After introduction of a slip, the charge must remain in contact with the entire object forming cavity of the mold until, by the process of absorption of the water from the slip by the mold or by forcing the water into the mold as a result of extreme slip pressures, the charge within takes on the character of a solid throughout, at which time the formed charge commences to undergo normal shrinkage. If at this time there is any tendency in the formed charge or object to contract and bind upon any of a plurality of mold sections, such as the core portion of a mold forming the interior of an object, such a section 15 may be removed manually, by exercising extreme care, from contact with the object. Such mold sections have been withdrawn from the formed object by pressurizing a section by means of a conduit extending into the mold section. When such a type of mold section withdrawal is practiced, the object is backed up by other supporting mold sections and the entire mold is in the closed position when pressurized.

20 Mold sections are also sometimes removed so that the exposed ware with its supporting mold members may be subjected to a drying treatment to hasten the final shrinkage release of the formed object. Although it is possible to remove special sections of the mold soon after solidification, the object for a time remains in an easily deformable condition and adheres to the remaining mold members until finally released by the shrinkage inherent in the object.

25 The molds are usually worked in the proximity

of a drying means so as to keep the molds in a workable condition.

Dry molds are most imperative for gravity casting which depends largely upon the absorption properties of the plaster and where at best production may not exceed 6 pieces per mold per day, and may be no greater than 1 piece per day. Although it is true that dry molds are not as necessary for pressure casting, the water being forced into the mold under pressure carries small colloidal particles and other harmful soluble materials into the pores and soon blocks them to further use.

The present invention has for an object the provision of a novel method and means for the manufacture of ceramic ware, wherein the above mentioned disadvantages are obviated.

A further object is to provide a novel method and apparatus for forming ceramic objects which may be employed in combination with present manufacture methods to increase markedly the production rate. The invention is particularly advantageous for combination with processes which are unsuccessful due to limitation in handling certain types of moldable materials such as are used in casting, which when handled often result in unsatisfactory object release from the mold, causing the object to warp or crack.

A further object is to provide a novel method and apparatus for the manufacture of ceramic objects wherein an object is removed from the mold with retention of integrity of shape of the object, lending to the most absolute product uniformity possible.

A further object is to provide a method and apparatus for the manufacture of ceramic ware wherein through quick release of the object from the mold, a high speed production rate is attained, without sacrificing the quality of product and with marked reduction of unit cost.

A further object is to provide a method and apparatus for forming ware wherein adherence of the formed object to the mold face or faces can be controlled by the operator, irrespective of shrinkage characteristics or density of the molded object.

A further object is to provide a novel method and apparatus for forming ware of irregular shape or thickness wherein the effect of differential shrinkage on separation of a formed object from the mold, is eliminated, and the number of molds necessary for accomplishing a continuous object forming operation is minimized.

A further object is to provide a novel method for effecting the quick release of ceramic objects from mold surfaces, without injuring the ware, before normal shrinkage occurs.

A further object is to provide a novel method and apparatus for the manufacture of asymmetrically shaped clay objects.

Still a further object is to provide a novel mold for use in casting ceramic objects which is inexpensively and easily fabricated, permitting of frequent design changes, and which is adaptable for use with presently employed casting processes and apparatus.

An additional object resides in the provision of means and method for vacuum removal of absorbed fluids from mold sections, such as are expressed from the molded object into the mold sections and subsequently purging remaining fluids not previously evacuated from the mold sections.

An additional and related object resides in the initial reduction of pressures within mold sec-

tions to permit absorption thereby, enhancing setting of an introduced slip by increasing absorptive quality of the mold sections.

Still another object of the invention relates to the cleansing of the pores of the mold, following casting, a desired purging action eliminating sealing of porous molding surfaces by adjacent colloidal particles, and other harmful soluble impurities.

Another object of the invention is to provide a means for increasing ceramic mold life by the continual reduction of saturation of a mold or molds during use, avoiding reliance upon expensive drying equipment.

Other objects and advantages of the present invention will be found in the following detailed description thereof and the accompanying drawings, wherein:

Figure 1 is a vertical section of the mold of the present invention, with the male and female mold sections brought together in clamping engagement;

Figure 2 is a partial top plan view of the female mold taken along the line 2-2 of Figure 1;

Figure 3 is a perspective view of a portion of fluid pressure conduit employed in forming the mold.

Figure 4 is a vertical section of the invention wherein multiple casting sections in excess of two are employed;

Figure 5 is a partial top plan view of the modification shown in Figure 4 taken along the line 5-5 of Figure 4.

In its broadest application, the invention comprises a novel method and means of separating ceramic objects from mold surfaces by the application of fluid pressure uniformly against the face of the formed object desired to be separated controlling the pressure in selected areas in accordance with the requirements of object thickness and shape. The source of pressure is preferably so disposed in relation to the contour and any selected area of the object as to provide a predictable, controlled force in the form of a pressure blanket exerted simultaneously across the entire surface area of the ceramic object, in accordance with a pre-selected pressure pattern, whereby release of the object from the mold surface is accomplished without impairing undue shock or strain to the object or any part thereof.

The invention may be employed satisfactorily with known forming processes such as casting under varying conditions wherein the casting materials are tempered with water or other mediums and which normally employ shrinkage release of the object from the mold. Such old processes are characterized by extremely slow rate of production, due to the inability to release the ware from the casting molds are normal shrinkage which occurs by the elapse of time.

However, the invention is most advantageously employed with forming processes wherein uniform shrinkage release of the object from the mold is difficult or impossible. The invention permits of employing mass production methods without a great need for many duplicate molds.

An ordinary casting operation that formerly took hours for a single object now for the first time can be accomplished in minutes. For instance, the art of pressure casting had practically become obscure until the present invention. Now, however, long mold life, clear post-casting mold surfaces are made readily available and there is a revival of a valuable art.

The invention may be employed with gravity

solid casting, drain casting, and external pressure solid casting where the slip used is of a higher specific gravity than normally employed in gravity casting. For purposes of illustration, the invention will be described as employed in external pressure and gravity pressure casting, the other methods and devices for carrying out related processes having been described in our United States Patent No. 2,584,199 entitled Method and Apparatus for Making Ware, issued February 5, 1952. It will be readily apparent, however, that the principles of the invention may be applied equally well to other methods of forming ceramic ware.

Referring to the drawings, the numeral 10 refers generally to a mold constructed in accordance with the invention, including a top or female mold section 12 and a bottom male mold section 14. Each mold section is formed in a casing 16, which may be constructed of any corrosion resistant material such as alloy steel, which may be assembled by welding. In one form of the invention the casings 16 are perforated as at 18 to facilitate purging in the manufacture of the mold body and to eliminate the development of interfering back pressures in the passage of fluid pressure through the mold for the release of ware and cleansing of the molding face of the mold body.

In another form of the invention, the casings 16 are sealed to retain pressure and liquid seepage during a casting operation.

The bodies 12 and 14 of the apparatus are formed of a material capable of hardening upon standing to form a solid porous and permeable element characterized by an ability to absorb moisture. A high grade of gypsum plaster or other suitable hydraulic setting cements may be employed. It is preferred to use a hard gypsum cement rather than soft plaster in view of its extreme hardness. Such a cement markedly prolongs the life of the mold. The plaster body should have high permeability and porosity, in order to attain the desired speed of operation of the mold. A preferred manner of forming the mold body is set forth in our copending application for patent Serial No. 108,228 entitled Treatment of Plaster Molds, filed August 2, 1949, now Patent No. 2,632,209. Such a process enables the use of dense hard plasters with controlled porosity.

The mold bodies 12 and 14 are provided with molding faces 20 and 22 by impression with suitable forms prior to hardening of the mold material. A cavity 24 is formed by the opposed molding faces 20 and 22, the cavity being sealed as at 26, where complementary surfaces of the respective mold bodies engage. Mold section 12 forms channel 28 which passes from the exterior of the casing 16 inwardly to the molding face 22. This channel 28 is employed to introduce slip under pressure into cavity 24. The channel walls 30 may be impregnated with suitable sealers to render them impervious to slip and to fluids. A conduit 32 is threaded into the cylindrical wall 30 of channel 28 providing valved passage for the slip from a pressurized reservoir 36. The flow control valve is designated as at 34. Slip may be introduced to the reservoir through an inlet conduit 38. The reservoir is pressurized by means not shown.

Clamping means 42 are attached to the exterior of the casings 16 to secure the mold bodies together. The clamping means may be a conventional butterfly nut-clamp arrangement.

In accordance with the present invention, fluid

pressure means are formed in the plaster bodies 12 and 14 for effecting removal of a clay object 40 from either or both of the mold faces 20 and 22, preferably prior to shrinkage normally occurring upon losing a portion of water of plasticity of the clay. Said means include a conduit 44 having an extension 46 passing through the casing of the mold body to a source of fluid pressure, not shown. The conduit 44 may preferably comprise a tubular member formed of an easily workable material which is corrosion resistant, such as a metal. The conduit 44 may be supported against radial displacement by one or more bracket members 45. The bracket 45 is formed to engage with any section of the conduit in order primarily to secure the conduit 44 firmly during formation and as the plaster mold hardens. The plaster casts 12 and 14 may be locked in the mold by dimpling the casings 16 as at different portions thereof 19, thereby preventing accidental displacement of the plaster casts in or from the molds upon the application of fluid pressures to the conduit 44.

Referring to Figures 2 and 3, the conduit 44 is apertured as at 48 along its length, the apertures opening into the body of the plaster molds. The apertures 48 are formed to provide a plurality of streams of fluid pressure in such a manner to provide an evenly dispersed blanket of pressure across the face of the clay object 40 adjacent the mold surfaces 20 and 22. The conduit 44 is pre-shaped to provide evenly spaced sources of fluid pressure about the entire face of the object 40. To accomplish this, the conduit 44 in one configuration, preferably is formed as a helix, with the coils thereof positioned internally of a mold section away from the face of the mold section but generally parallel to the contour of the clay object 40. In some instances, the conduit will be wound concentrically about itself as shown at the top of the mold body 12.

The spacing and size of the pressure apertures 48 and the distance between a section of the conduit 44 and the adjacent face of the clay object 40 and the spacing between related portions of the conduit determine the amount of fluid pressure which will be exerted on a portion of the clay object. By adjusting these variables, a controlled adherence of the clay object to the mold surfaces is accomplished. The operator may obtain adherence of any portion of the ware to any desired part of the mold for a preferred length of time, by exercise of this available control of the ware releasing pressure. Thus, regardless of the relative or differential thicknesses of the several parts of the ware, as for example the beaker shown in Figure 1, a fully controlled quick release of the object from the mold may be accomplished, without danger of injury to the ware from the ever present tendency to crack at the thin points, upon the application of pressures thereto. It will be appreciated that full release is not attempted herein until such time as the setting may have been effected and until the clamps have been loosened sufficiently to allow free release action.

As shown in Figure 3, it is preferred to enclose the conduit 44 with a wrapping of permeable fabric material such as gauze 50. The gauze serves to maintain the apertures 48 free from obstruction through the accumulation of particles of plaster, and provides a pressure chamber between the plaster and the conduit 44. Such a chamber facilitates building up of a fluid pressure head outside the conduit 44 in the body of the porous plaster mold in the direction of the mold face, accelerating the passage of the fluid pressure

through the body of the mold. The conduit 44 may be plugged to form a dead end in the mold body. Other forms of conduits may be employed including foraminous tubing of sufficiently rigidity to be self supporting.

The method of manufacture of a preferred mold body and the structure thereof is more fully disclosed and claimed in our United States Patent No. 2,584,110 entitled "Mold and Method of Manufacture" issued February 5, 1952. It is pointed out therein that a conduit such as 44 may also be formed advantageously by casting with wax or a low melting point metal alloy including a bismuth alloy, removable by subjecting the mold to elevated temperatures as soon as the plaster hardens.

A modification of the invention is shown in Figures 4 and 5 of the drawings. A mold generally indicated as at 60 comprises mold sections 62, 64 and 66. Each mold section is provided with a casing 68 which may be constructed of any corrosion-resistant material. The casings may be perforated or not depending upon the type of casting desired.

Mold section 62 has a molding face 70 cooperably disposed with molding face 72 of mold section 64. In this particular modification, mold section 66 engages receiving surfaces of mold sections 62 and 64, the mold section 66 forming a male molding surface as at 74. The molding surfaces 70, 72 and 74 together form a cavity 76 suitable for receiving slip either under pressure or by gravity feed as shown. In the drawings shown, the mold 60 is completely assembled for casting, the cavity 76 containing by way of illustration, a slip 100 which has been introduced by gravity feed.

In the modification in Figures 4 and 5, a funnel portion 78, leading into a channel 80, has been formed in the mold sections 62 and 64 respectively during hardening of the porous materials comprising the mold sections. As in the former construction shown in Figures 1 and 2, so here the funnel and channel portions are rendered impermeable, being impregnated with a suitable coating. The mold sections are joined as at 82 each mold section having one or more protrusions or recesses corresponding with mating portions of other mold sections to provide stability to the mold.

In the present modification, fluid pressure means generally indicated as at 84 passes through the casing 68 by means of extension 86. The fluid pressure means 84 comprises a tubular member substantially as hereinbefore described. In the mold bodies 62 and 64 respectively, the conduit 84 passes arcuately back and forth across the semi-circular section thereof, the conduit being spaced at distances critical from the molding face 70 of the mold body. As has been previously explained, the proximity of the conduit member to the molding face of the mold is dependent upon the porosity desired in the end mold product and the desired release pressures to be uniformly obtained at the mold face. It may be apparent that the conduit will be disposed more proximate the mold face at portions adjacent heavier portions of the ware and more distant at portions adjacent thinner portions of the ware. However, the conduit may be placed equidistant from the molding face or otherwise disposed to effect uniform release. Mold section 66 contains a conduit 84 substantially similar to that defined for the mold body 62. In the mold section 66 the conduit 84 is likewise strategically displaced within the

mold section distant from the molding face 74 thereof. In this instance, however, it is preferred that the conduit member be secured helically about the interior of the mold section and critically distant adjacent the molding surface 74. The pressure apertures are indicated as at 88. Likewise the disposition of the conduit through mold bodies 62 and 64 respectively is indicated as at 90 in Figure 5.

One or more bracket members 92 protrude inwardly from the casing 68 of each of the respective mold sections to provide support to the tubing structure within the mold during the formation thereof. In addition there are provided recesses 94 strategically about the interior of the casing 68 to secure the mold against movement within the casing member.

In operation, the principle of the invention may be employed in the manufacture of ware from a variety of casting materials. As separation from the mold is accomplished prior to shrinkage release of the clay object, the unpredictable results obtaining from the differing contraction properties of different types of clays, are eliminated as a production factor. Accordingly, the invention may be used to speed up all known casting methods of ware manufacture, which normally require an hour or more for adequate object shrinkage to occur before the clay object separates from the mold.

A preferred type of slip used in a pressure-casting operation is normally of greater density than that employed in gravity castings. Accordingly, and in keeping with current practice hereunder, a "livery" slip may be forced under pressure through the conduit and into the cavity formed by the opposed molding faces of the mold sections. At this time, the mold sections may be evacuated by means of the conduits within to render the mold sections more absorptive thus accelerating the setting action of the slip, the slip being under positive pressure within the cavity formed by the respective mold faces. The slip remains in contact with the mold cavity until the charge within assumes the character of a solid throughout at which time it commences to undergo normal shrinkage.

Now after we have cast a ware object, we seek to remove mold sections from the ware, in preparation for the final release of the ware, by means of passing fluid pressure through at least one of the mold sections thereby leaving the formed ware upon another supporting mold section. The following step must be undertaken to remove the formed ware from the ware supporting mold section. The supporting mold now has fluid pressure passed therethrough to the molding face thereof, against the formed ware to release the ware from the supporting mold section.

It will be appreciated that the foregoing operative description may be employed to describe the process as applied to gravity casting and drain casting.

A study of the structure of the invention will disclose that a vacuum may be created in either one of the molding units to the exclusion of the other and that fluid pressures may be applied to either surface of a cast object, dependent upon the qualities thereof desired. Various adaptations in structure and operation though not specifically described herein may be made without departing from the spirit of the invention.

It will be observed that the present invention provides novel methods and means for forming clay objects. Possible specific uses include the

manufacture of dinner ware, art ware including sculpture, decorative tile, terra cotta, refractories, and electrical porcelains. The controlled adherence principle of the invention may be employed to advantage with all ware forming processes, allowing release of the ware from the mold sections at any point in the manufacturing operation subsequent to casting.

Other obvious adaptations of the invention will occur to one familiar with the art. The invention comprehends the substitution of equivalents, where possible, and is to be limited only as defined in the appended claim.

This application is a continuation in part of copending Blackburn and Steele application Serial No. 265,766 filed January 10, 1952, which was copending with Blackburn and Steele application Serial No. 737,544, now Patent No. 2,584,110, and Blackburn and Steele application Serial No. 737,174, now Patent No. 2,584,109.

We claim:

A method for casting green ceramic ware in a porous mold and for separating the cast ware completely from the mold after the ware has become self-sustaining and, independently of the shrinkage of the ware, to promptly free the mold for reuse, which comprises causing a slip to fill a ware-forming cavity defined by a plurality of

5
10
15

permeable mold members, maintaining said slip in said cavity in contact with said mold members for a time sufficient to render said slip self-sustaining and form an easily deformable green piece of ware, thereafter before said piece shrinks appreciably (a) passing a fluid under pressure through a first of said mold parts to release said piece therefrom and (b) separating said first mold part from said piece to leave said piece supported only by the remaining mold parts and (c) thereafter passing a fluid under pressure through said remaining mold parts to separate the unsupported piece completely therefrom and free the mold for reuse in the formation of additional pieces of ware.

ANDREW R. BLACKBURN.
RICHARD E. STEELE.
